LOOSE-LEAF FILING INDEX

William F. D. Ackermann, Kaylor, S. Dak.

Application March 9, 1939, Serial No. 260,870

2 Claims. (Cl. 129—16)

The invention relates to a loose-leaf filing index or device and more especially to a visible, adjustable and loose-leaf filing index.

The primary object of the invention is the provision of an index or device of this character, wherein a loose-leaf for a binder carries holders, these being adaptable for receiving and making visible items upon separate sheets, cards or the like, these being readily changeable and so constructed than an individual item may expose one or more lines for receiving written or otherwise impressed data freely accessible, thereby assuring a handy system of filing.

Another object of the invention is the provision of an index or device of this character, wherein new items can be filled without the necessity of removing or refiling any of those items held in the device, the index being in pocket form and all items visible so that individual filings do not have to be handled, thereby saving time in making reference thereto and preventing wear and tear in the handling with the result that the records filed are maintained neat and clean.

A further object of the invention is the provision of an index or device of this character, wherein a series of cards or others items of memoranda is removably held and arranged in a manner that the memoranda noted or items may be added to or removed from time to time or substitution had at any point without disturbing the general classification as set up in the index or device and any selected memorandum or item can be examined without requiring the handling individually thereof or the turning of pages for locating such memorandum or item as is generally required in book records.

A still further object of the invention is the provision of an index or device of this character, wherein the setup thereof renders it compact, conveniently accessible, assuring the handling of items with dispatch and with minimum labor on the part of a user, the index or device being susceptible of expansion for increasing filings and avoiding misplacement of items, and providing a ready reference to selected or all of the items held thereby.

A still further object of the invention is the provision of an index or device of this character, which is simple in construction, novel in its make-up, thoroughly reliable and efficient in operation, convenient in the handling thereof, assuring ready and easy reference to filings, strong, durable, and inexpensive to manufacture and install.

With these and other objects in view, the in- 55

vention consists in the features of construction, combination and arrangement of parts as will be hereinafter more fully described, illustrated in the accompanying drawings, which disclose the preferred and modified forms of embodiment of the invention and pointed out in the claims hereunto appended.

In the accompanying drawings:

Figure 1 is an elevation partly in section of an index or device constructed in accordance with the invention.

Figure 1 is a sectional view taken on the line 2—2 of Figure 1 looking in the direction of the arrows.

Figure 3 is a sectional view of the loose leaf alone taken on the line 3—3 of Figure 1 looking in the direction of the arrows.

Figure 4 is an elevation of one of the holders associated with the index or device.

Figure 5 is a view similar to Figure 4 looking toward the opposite side thereof.

Figure 6 is a detail plan view of a blank form from which the holder, as constructed in Figures 4 and 5, is made.

Figure 7 is a sectional view on the line 7—7 of Figure 4 looking in the direction of the arrows.

Similar reference characters indicate corresponding parts throughout the several views in the drawings.

Referring to the drawings in detail, particularly Figures 1 to 7, inclusive, A designates one of a series of loose leaves for a binder (not shown) and B a holder for a card, memorandum or other record bearing medium, respectively, for association with each other and constituting the present invention.

The conveniences of the loose-leaf book as well as the card system have become thoroughly established, being required for present day methods of business enterprises that the same be used conjunctively, and the joined use and the construction of each being hereinafter fully described.

Each loose leaf A is preferably formed from relatively stiff fibrous or like sheets of material, these including the outside sheets 10 and 11, respectively, and an intermediate sheet 12, being joined in any suitable manner face to face and in matched relation to each other. The outside sheets are plaited adjacent the opposite edges of the leaf A and in parallel relation to each other to provide retaining folds 13, which extend throughout the area of the leaf A in one direction and the said folds 13 next to the lowermost edge of the leaf being cut and folded diagonally at

14 to provide stop tongues 15, these being formed from the inner plies of the plaits and united to the face thereof of the sections 10 and 11 next thereto while the plaits or folds 13 at the uppermost edge of the sheet are free for admission of the holder B for slidable interfitting with the said folds 13 of the leaf A in a manner presently described.

The folds 13 are at opposite sides of the leaf A and coextend in spaced parallel relation to each other from the uppermost edge of the leaf to a point close to the lowermost edge thereof. It is preferable that the leaf A be perforated at intervals following one side edge thereof but removed therefrom and said perforations reinforced by eyelets 16 so that a plurality of leaves may be attached in a temporary binder (not shown) and of any desirable form, the eyelets 16 accommodating the loose-leaf fastening medium (not shown) as may be employed for loose-leaf binding in a binder.

The leaf A at the free turning edge thereof opposite to the edge having associated therewith the eyelets carries a marker tab 17 for indexing indicia, as is common in indexing leaves of a book, in this instance the indicia being the letter A, as at 18.

The holder B for a memorandum slip, card or the like, as, for example, at 19, comprises a racking frontal portion 20 and an interfitting backing portion 21, respectively, the latter portion being provided with a tab extension 22 while the portion 20 is provided with a leg or prop 23. This holder B is made from a single blank of sheet material 24 having reversely tapered ends, one constituting the tab extension 22 and the other the leg or prop 23. The blank is foldable along crease lines 25, 26 and 27, respectively, for producing the portions 20 and 21, respectively, the pull extension 22 and leg or prop 23, respectively. The blank 24 at opposite longer edges has the diagonal slits 28 meeting fold lines 29 which are parallel with each other longitudinally of the said blank and inwardly of the side edges thereof so that when the blank is folded first up along line 26 in Figure 6 and then these side edges are folded inwardly over the portion extending between the lines 26 and 27 there is produced racking plaits or folds 30 forwardly of the frontal portion 20 and stop lips 31 at the lowermost ends of the plaits or folds 30, these plaits and lips being inset with relation to runner wings 32 which are projected beyond the said folds or plaits 30 at opposite ends of the backing portion 21 for slidably fitting the plaits or folds 13 of the leaf A. These plaits or folds 13 are in overlapping relation to the wings 32 when the holder is fitted to the said leaf. The lips 31 are turned on crease lines 33 and fixed to the backing portion 21 so that the folds or plaits 30 will pocket

the card 19 when engaged therewith for carriage by the frontal portion 20 of said holder. The leg or prop 23 extends beneath the stop lips 31 when fastened to the portion 21 so that on the interfitting of a plurality of holders sandwiched between the frontal and backing portions 20 and 21 the cards 19 pocketed in the respective holders so interfitted will be stepped vertically with the uppermost portions visibly exposed, one above the other, when the said holders are carried upon the leaf A. The frontal portion is susceptible of vertical swing following the crease line 25 so that the card 19 in each holder will have its outermost face freely exposable for a major extent of the said cards excepting the end portions pocketed by the plaits or folds 30 of the holder and in this manner easy reference and visibility selectively of the cards is obtainable.

The exposed uppermost portions of the cards have present thereon suitable identifying indicia, as at 34, enabling ready selective reference to the cards racked in the index or device. It is preferable to have the leg or prop 23 attached permanently to the backing portion 21 so as to stiffen such flap for the lifting function thereof in the interfitting of the holders one within the other for indexing of memorandum slips, cards or the like in the association of these holders with the leaf A.

What is claimed is:

1. A card holder for a loose-leaf filing index, comprising a cut and folded body formed from a single sheet of relatively stiff fibrous material providing a backing portion and a racking frontal portion forwardly of and swingable on a horizontal axis relative to said backing portion, a leg extended below the axis of the swingable frontal portion, racking pleats at opposite ends of the frontal portion and disposed forwardly thereof, runner wings at opposite ends of the backing portion, and lips turned inwardly and upwardly rearwardly of the backing portion for effecting stops at the lower ends of the pleats.
2. A card holder for a loose-leaf filing index, comprising a cut and folded body formed from a single sheet of relatively stiff fibrous material providing a backing portion and a racking frontal portion forwardly of and swingable on a horizontal axis relative to said backing portion, a leg extended below the axis of the swingable frontal portion, racking pleats at opposite ends of the frontal portion and disposed forwardly thereof, runner wings at opposite ends of the backing portion, lips turned inwardly and upwardly rearwardly of the backing portion for effecting stops at the lower ends of the pleats, and an extension rising from the backing portion above the uppermost edge of the frontal portion.

WILLIAM F. D. ACKERMANN.
